UNITED STATES PATENT OFFICE

96,275

DESIGN FOR A BUCKLE

Solomon Putman, Newark, N. J.

Application April 26, 1935, Serial No. 56,575

Term of patent 3½ years

To all whom it may concern:

Be it known that I, Solomon Putman, a citizen of the United States and a resident of Newark, in the county of Essex and State of New Jersey, have invented a new, original, and ornamental Design for Buckles, of which the following is a specification, reference being had to the accompanying drawing forming part thereof.

I claim:

The ornamental design for a buckle as shown.

SOLOMON PUTMAN.
